Assistant Examiner — Molly Loch

(57) **CLAIM**

We claim the ornamental design for the fire alarm emergency LED flasher, as shown and described.

DESCRIPTION

FIG. 1 is a left-hand front perspective view of the design for an fire alarm emergency LED flasher.

FIG. 2 is a right-hand front perspective view of the design for an fire alarm emergency LED flasher,

FIG. 3 is a right-hand rear perspective view of the design for an fire alarm emergency LED flasher,

FIG. 4 is a front view,

FIG. 5 is a rear view,

FIG. 6 is a left-hand side view,

FIG. 7 is a right-hand side view,

FIG. 8 is a top view; and,

FIG. 9 is a bottom view.

1 Claim, 9 Drawing Sheets
